CLAIM

The ornamental design for a slip resistant sole, as shown and described.

DESCRIPTION

FIG. 1 is a bottom plan view of a slip resistant sole design of the invention;

FIG. 2 is a first side view of a slip resistant sole design of FIG. 1;

FIG. 3 is a second side view of a slip resistant sole design of FIG. 1;

FIG. 4 is a front end view of a slip resistant sole design of FIG. 1; and,

FIG. 5 is a rear end of the embodiment a slip resistant sole design of FIG. 1.

The broken line showing of a shoe upper in FIGS. 1-5 is for illustrative purposes only and forms no part of the claimed design.

FIG. 1

FIG. 4

FIG. 5
